FRUIT PEELER

Albert P. Ruggieri, 201 Spruce Road,
Flourtown, Pa. 19031

Filed June 27, 1968, Ser. No. 12,526

Term of patent 7 years

Int. Cl. D7—03

U.S. Cl. D89—1

FIG. 1 is a side, perspective view of the fruit peeler embodying my new design;

FIG. 2 is another perspective view thereof but viewed from the front;

FIG. 3 is a side view thereof; and

FIG. 4 is a sectional view taken along the line 4—4 in FIG. 1.

I claim:

The ornamental design for a fruit peeler, as shown.
